Specification for Design.

Patented Oct. 31, 1916.

Application filed October 18, 1915. Serial No. 56,615. Term of patent 3½ years.

To all whom it may concern:

Be it known that I, **WILLIAM S. HARLEY**, a citizen of the United States, residing at Milwaukee, in the county of Milwaukee and State of Wisconsin, have invented a new, original, and ornamental Design for Motor-Cycle Frames, of which the following is a specification, reference being had to the accompanying drawing, forming part thereof.

The figure is a side elevation of a motor-cycle frame, showing my new design.

I claim:

The ornamental design for a motorcycle frame, as shown.

In testimony that I claim the foregoing I have hereunto set my hand at Milwaukee, in the county of Milwaukee and State of Wisconsin, in the presence of two witnesses.

WILLIAM S. HARLEY.

Witnesses:

**EDWIN F. CASPER,
E. B. ELSNER.**
